UNITED STATES PATENT OFFICE.

WALTER VAN WIE, OF OAKLAND, CALIFORNIA.

ADJUSTABLE COUNTERBALANCE RADIUS-CRANE.

No. 911,093.

Specification of Letters Patent.

Patented Feb. 2, 1909.

Application filed April 25, 1908. Serial No. 429,220.

To all whom it may concern:

Be it known that I, WALTER VAN WIE, a citizen of the United States, residing at Oakland, in the county of Alameda and State of California, have invented a new and useful Improvement in Adjustable Counterbalance Radius-Cranes, of which the following is a specification.

This invention relates to an adjustable horizontal swinging radius counterbalanced crane, which is an improvement upon a radius crane which is subject matter of a separate application Serial Number 429,699.

The invention consists in the novel features of construction hereinafter described, pointed out in the claim and shown in the accompanying drawings, in which—

Figure 1 is a side elevation illustrating the use of the invention. Fig. 2 is a plan view 20 of the device, certain supporting bolts being shown in section.

In these drawings 1 represents a curved track, and 2 a horizontal swinging beam, said beam swinging in a horizontal plane and 25 being supported at one end by a swiveled bracket 3. The beam 2 carries a shaft 4 having a wheel 5 which travels upon the track 1 and a pulley 6 over which runs an operating chain 6^a. These parts are substantially similar to parts shown and described in the application above referred to. The improvement designed to be covered by this application resides in the following additional features:—In the bracket 3 is pivotally mounted a depending rod 7 to the lower end of which is pivotally mounted a weight beam 8. To one end of this beam is secured a hoisting cable 9 which cable runs over suitable pulleys 10 carried by the beam 2 and which is to be connected to the article to be lifted. A chain 11 is carried by the beam 2 in position to be engaged by an adjustable hook 12 carried by the free end of the weight beam 8, and which hook is adjusted by means of a bench nut 13. A traveling carriage 14 is mounted upon the weight beam 8 and carries a counter balance weight 15, and a threaded rod 16 carried by and beneath the beam 8 works through a suitable

50 nut 17 carried by the carriage 14 and serves to move said carriage along the beam 8.

The rod 16 is rotated by means of a hand wheel 16^a.

The operation of the device is briefly as follows:—The cable 9 is secured to the work 55 to be lifted and by turning the nut 13 the hook 12 may be disengaged from a link of the chain 11 thus throwing the weight of the weight beam and parts carried thereby upon the cable 9. By means of the wheel 16^a the 60 carriage 14 may be run towards the free end of the beam 8 thus overbalancing the weight of the article to be lifted and throwing the parts into the position shown in dotted lines in Fig. 1. By means of the chain 7, pulley 6, 65 shaft 4 and wheel 5, the beam 2 and the article to be supported by the cable 9 may be swung in a circle until the work is above the floor or other surface upon which it is to be deposited. The weight 15 is then run back 70 allowing the article lifted to gradually descend to the floor and the hook 12 is again engaged with a link of the chain 11 and the cable 9 disengaged from the casting or other article to which it may have been attached. 75

Other convenient methods of handling heavy articles by means of this device will be obvious to those familiar with hoisting devices.

Having thus fully described my invention, 80 what I claim as new and desire to secure by Letters Patent, is:—

A device of the kind described comprising a beam traveling horizontally about a pivot point, a depending rod pivotally connected 85 in alignment with the pivotal point of the beam, a second beam pivotally connected at one end to the depending rod and swinging vertically, pulleys carried by the first mentioned beam, a hoisting cable running over 90 said pulleys and secured to the free end of the second beam, an adjustable weight working upon the second beam, a chain depending from the first mentioned beam and an adjustable hook carried by the free end of 95 the second mentioned beam in position to engage said chain.

WALTER VAN WIE.
